UNITED STATES PATENT OFFICE.

ROY W. CHESNUT, OF EAST ORANGE, NEW JERSEY, ASSIGNOR TO WESTERN ELECTRIC COMPANY, INCORPORATED, OF NEW YORK, N. Y., A CORPORATION OF NEW YORK.

CIRCUIT FOR ELECTRIC-DISCHARGE DEVICES.

Application filed May 26, 1923. Serial No. 641,548.

This invention relates to circuits for electric discharge devices such as vacuum tubes of the three-electrode type.

An object of this invention is to reduce noise in the vacuum tube circuit, due, for example, to fluctuations in voltage or current supplied to the tube for heating the filament or cathode.

The form of this invention hereinafter described in detail is embodied in a vacuum tube repeater circuit of the type in which the negative grid potential is obtained by the potential drop across the terminal of an impedance such as a resistance included in the circuit which supplies heating current to the cathode. The constancy of the direct current potential difference between the grid and the cathode will in such a case depend upon the constancy of the heating current supplied to the filament so that trouble may be experienced if the current supply fluctuates for any reason.

In accordance with one form of this invention, noise in a vacuum tube transmission circuit due to cathode current fluctuations is substantially prevented by connecting the grid or control electrode effectively to the midpoint of the cathode for all alternating current components of the cathode current while connecting the control electrode to one side of the cathode for the direct current component of the heating current, thereby enabling the direct current potential of the control electrode to be obtained as described above by the drop in potential across the terminals of the resistance in the cathode heating circuit. One way this may be accomplished is by connecting the control electrode through a condenser to the midpoint of an impedance connected across the filament terminals and also by connecting the control electrode to one side of the cathode through a retard coil or other device of high impedance to alternating current and low impedance to direct current.

The drawing illustrates this invention embodied in a transmission circuit employing a vacuum tube amplifier or repeater of the three-electrode type.

Referring in detail to the drawing, a vacuum tube 3 is disclosed having an anode 4, a cathode 5 and a grid or control electrode 6. The input circuit for the tube comprising control electrode 6 and cathode 5 is connected to an incoming line 8 by an input

step-up transformer 9, while the output circuit comprising the anode 4 and cathode 5 is connected to an outgoing line 10 by an output transformer 11. Such an arrangement as is well known in the art enables the tube 3 to impress upon the outgoing line 10 currents corresponding to those present in line 8 but amplified in form. The output circuit battery 12 is connected between the anode and cathode in the usual manner. The cathode 5 is heated by current from a suitable source of voltage 13.

Trouble in such a vacuum tube circuit is occasionally encountered due to cathode battery noise disturbing the circuit due to the cathode battery current actually changing rapidly by small amounts, which changes react upon the input circuit or the output circuit of the tube to produce alternating current potentials in the transmission circuit. The presence of this foreign alternating current potentials in the transmission circuit is, of course, objectionable since it will be transmitted along with the amplified signals. The undesirable noise produced by fluctuations in the cathode heating current is especially pronounced when the control electrode of the tube is maintained at a negative potential with respect to the cathode by a resistance drop in the cathode heating circuit. In the vacuum tube circuit shown in the drawing, a resistance 14 is included both in the input circuit and in the filament heating circuit, as a result of which, the control electrode 6 is maintained at a negative potential with respect to the cathode 5 by the voltage drop in the resistance, due to current from the battery 13. If, now, the current from the battery 13 is subjected to rapid fluctuations, the potential across the terminals of resistance 14 also tends to fluctuate, and to thereby impress the fluctuations in potential upon the control electrode and cause them to be amplified along with the signal currents received from the incoming line 8.

In accordance with this invention, however, these undesirable fluctuations due to the cathode heating current are prevented by connecting the control electrode 6 effectively to the midpoint of cathode 5 by a path of high impedance to direct current but of low impedance to alternating current. This path may comprise, for example, a capacity 15 connected to the midpoint of a

resistance 16 which is shunted across the terminals of the cathode 5. In order that the negative grid potential may be still obtained by the drop across the terminals of 5 resistance 14, in spite of the alternating current connection effectively to the midpoint of the cathode, the grid 6 is connected to the terminal of resistance 14 away from the cathode by a path of high impedance 10 to alternating current but of low impedance to direct current. In the drawing, this path is shown to comprise a retard coil 16'. With the retard coil 16' and condenser 15 connected as shown, the control electrode will 15 still take the steady potential of the point 17 in the filament heating circuit but any rapid fluctuations in the potential at the point 17 will not reach the grid 6 because the grid is connected to the point 17 through 20 a retard coil or other apparatus of high impedance to alternating current and of low impedance to direct current. The grid will, of course, take the instantaneous fluctuations in potential at the point of the circuit corresponding to the midpoint of the filament because it is connected to the point 18 through 25 a condenser 15 or other apparatus of low impedance to alternating current and of high impedance to direct current. By this arrangement, it is seen that it is possible to obtain the advantage of a resistance drop in the filament heating circuit to provide 30 a substitute for the usual "C" battery and at the same time having the grid connected to the midpoint of the filament to reduce noise.

It is to be understood, however, that this invention may possess other forms differing 40 widely from the particular embodiment described above without departing in anywise from the spirit of this invention as defined in the appended claims.

The invention claimed is:

1. An electric discharge device having an 45 anode, a cathode and a control electrode, means for connecting said control electrode effectively to the midpoint of said cathode for alternating current potentials, and means for connecting said control electrode to one side of said cathode for direct current potentials.

2. In combination, an electric discharge 55 device having an anode, a cathode and a control electrode, a path from said control electrode to the midpoint of said cathode of low impedance to alternating current and a high impedance to direct current, and a path of low impedance to direct current and a high impedance to alternating current from said control electrode to one side of said cathode.

3. In combination, an electric discharge 65 device having an anode, a cathode and a control electrode, a heating current source for said cathode, a divided input circuit connecting said control electrode and said

cathode and comprising means including a retard coil and a resistance traversed by said heating current, for maintaining a definite direct current potential difference between said control electrode and said cathode, and means for connecting said control electrode effectively to the midpoint of said cathode for alternating potentials. 70

4. An electric discharge device having an anode, a cathode and a control electrode, 75 heating current supply leads for said cathode, an input circuit connected between said control electrode and said cathode, an impedance connected in series circuit relation with said supply leads and between the control electrode and cathode in said input circuit, and a by-pass around said impedance comprising a condenser for preventing fluctuations of the current supplied by said supply leads to the cathode from changing the 80 potential of the control electrode with respect to the cathode.

5. An electric discharge device having an anode, a cathode and a control electrode, 85 heating current supply leads for said cathode, an input circuit connected between said control electrode and said cathode, an impedance common to said supply leads and said input circuit, and a by-pass around said impedance connected effectively to the midpoint of said cathode, said by-pass being of 90 high impedance to direct current.

6. An electric discharge device having an anode, a cathode and a control electrode, current supply leads for supplying heating current to said cathode, an input circuit connecting said control electrode and said cathode and comprising an impedance connected in series circuit relation with said supply leads and between said cathode and control 100 electrode, and means comprising a circuit having a high impedance to direct current for preventing rapid fluctuations in the heating current supplied to the cathode from substantially changing the potential of said control electrode with respect to the cathode. 105

7. In combination, an electric discharge 110 device having an anode, a cathode and a control electrode, current supply leads for supplying heating current to said cathode, an input circuit connecting said control electrode and said cathode comprising an impedance connected in said supply leads, means between said impedance and said control electrode of high impedance to alternating current and low impedance to direct current and a by-pass around said means and said impedance, said by-pass being of high impedance to direct current and low impedance to alternating current. 115

8. In combination, an electric discharge 120 device having an anode, a cathode and a control electrode, current supply leads for supplying heating current to said cathode, an input circuit connecting said control elec- 125

trode and said cathode comprising an impedance connected in said supply leads, means between said impedance and said control electrode of high impedance to alternating current and low impedance to direct current, and a by-pass around said impedance and said means connected effectively to the midpoint of said cathode.

9. In combination, an electric discharge device having an anode, a cathode and a control electrode, current supply leads for supplying heating current to said cathode, an input circuit connected to said control elec-

trode and said cathode and comprising an impedance common to said supply leads, a retard coil in said input circuit and included between said control electrode and said impedance, an impedance connected across the terminals of said cathode and a condenser connected around said first impedance and said retard coil and to the midpoint of said second impedance.

In witness whereof, I hereunto subscribe my name this 24th day of May A. D., 1923.

ROY W. CHESNUT.
